(57) CLAIM

We claim the ornamental design for a customizable container, as shown and described.

DESCRIPTION

FIG. 1 is a front and top perspective view of a second embodiment of a customizable container in accordance with the present invention;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the customizable container that form no part of the claim.
